WORK HOLDER FOR ARTICLE ATTACHING MACHINES

Hermann Gunther, Elizabeth, N. J., assignor to
The Singer Manufacturing Company, Elizabeth, N. J., a corporation of New Jersey

Application July 26, 1943, Serial No. 496,131

6 Claims. (Cl. 112—114)

This invention relates to work-holders for article-attaching machines and more particularly to a work-holder designed to hold articles each having a substantially circular periphery and a series of stitch-receiving apertures adjacent said periphery.

A releasing cone for a parachute is a good example of the type of articles which this improved clamp is designed to hold and the invention will, therefore, be shown and described in connection with such cones.

Parachute releasing cones, as usually constructed, each comprises a flat disk-like base and a cone proper which rises from the base with the bottom of the cone spaced inwardly from the periphery of the base. Intermediate the bottom of the cone and the periphery of the base, the base is formed with eight equally spaced apertures through which stitches are formed to attach the cone to a portion of the parachute casing.

When attaching such cones by machine it is essential that the cones be so accurately located with respect to the stitch-forming mechanism that the needle, in certain predetermined reciprocations, will enter the stitch-receiving apertures in the disk-like base of the cone, otherwise the needle will strike the base and be broken.

Considerable difficulty has been experienced in quantity production of such work-holders so that entry of the needle into the stitch-receiving apertures will be assured. This is due to the fact that any slight variation in the parts of the work-holder or in their assembly may dislocate the cone sufficiently to cause mis-alignment between one or more of the stitch-receiving holes and the needle.

A primary object of this invention therefore, is to provide a work-holder for this purpose, which readily may be made and assembled in quantities but which will provide means for individually adjusting the article-holding jaws to compensate for slight inaccuracies in manufacture or assembly and to correct any resultant mis-alignment between the needle and the stitch-receiving apertures in the article.

Article attaching machines of the type referred to in this application are commonly provided with means for effecting adjustment of the work-holder, as a whole, both lengthwise and crosswise of the work-supporting arm. This invention therefore is concerned primarily with means for effecting relative adjustment of the work-holding jaws whereby the article to be attached may be adjusted angularly.

With the above and other objects in view, as will hereinafter appear, the invention comprises the devices, combinations and arrangements of parts hereinafter set forth and illustrated in the accompanying drawing of a preferred embodiment of the invention, from which the several features of the invention and the advantages attained thereby will be readily understood by those skilled in the art.

In the drawing,

Fig. 1 is a side elevation of a portion of an article attaching machine fitted with a work-holder embodying the present invention.

Fig. 2 is an enlarged side view, partly in section, of a portion of the improved work-holder and parts associated therewith looking in the direction opposite to that in Fig. 1.

Fig. 3 is a top plan view of the front end portion of the improved work-holder, showing a parachute releasing cone held therein.

Fig. 4 is an under side view of portions of the work-holder shown in Fig. 3, the work-supporting feed-plate being omitted.

Fig. 5 is an enlarged transverse sectional view taken substantially on the line 5—5 of Fig. 3.

Fig. 6 is a perspective view of an article holding jaw and presser-foot forming a part of the improved work-holder.

Fig. 7 is a detail sectional view taken substantially on the line 7—7 of Fig. 5, showing one of the adjustably mounted article-holding jaws of the present work-holder.

Fig. 8 is a plan view of one of the parachute releasing cones which the present work-holder is designed to hold.

Fig. 9 is a plan view showing the cone disclosed in Fig. 8 attached to a piece of fabric by a series of machine made article-attaching stitches.

Referring more specifically to the drawing, the invention is disclosed as embodied in a work-holder for an article attaching machine including a horizontally disposed work-supporting arm 1, an upright standard 2, an overhanging bracket-arm 3 terminating at one end in a bracket-arm head 4. Reciprocably mounted in the head 4 is a needle-bar 5 carrying, at its lower end, an eye-pointed needle 6 which cooperates with a loop-taker (not shown), located in the free end of the arm 1, to form stitches. A throat-plate 7 is secured upon the forward end of the work-supporting arm and is provided with a needle-hole 8 through which the pointed and eyed end of the needle passes to cooperate with the loop-taker.

55 The work-holder is generally similar to the

work-holder disclosed in United States patent to Barron, No. 1,355,119, Oct. 12, 1920, and the means for shifting it lengthwise of the arm 1 is generally similar to that disclosed in United States patent to Sullivan No. 777,564, Dec. 13, 1904. Means also is provided for moving the forward end of the work-holder transversely of the arm 1. This last named means is similar to that disclosed in United States patent to Gunther, No. 2,116,889, May 10, 1938.

The work-holder comprises a slide-bar 9 mounted on the upper surface of the arm 1 and a work-supporting feed-plate 10 secured to the forward end thereof. The feed-plate rests upon and is movable over the throat-plate 7. Adjacent its rear end, the bar 9 carries a block 11 in which is loosely mounted the rear downturned end 12 of a forwardly projecting clamp-supporting bar 13 which is pressed toward the slide-bar 9 by the usual leaf-spring 14. The downturned end 12 of the bar 13 is fulcrumed at 15, in a notch formed in a plate 16 adjustably secured upon the slide-bar 9. Pivotaly mounted on screws 17 at the under side of the bar 13 are a pair of clamp-arms 18 each carrying, at its free forward end, an article-holding jaw 19, later to be described. Cooperating with the jaws 19 in holding the article, in this instance the parachute releasing cone C, is a third jaw 20, a portion of which also serves as a presser-foot for the material to which the cone is to be attached, as hereinafter will be described. The jaw 20 also serves as a stop to limit the inward movement of the cone when it is inserted between the jaws 19. The jaw 20 has an upright shank 21 which is adjustably secured, by screw 22, for vertical adjustment to an inverted L-shaped bracket 23. This bracket is secured, for horizontal adjustment on the forward end of the clamp-supporting bar 13, by a screw 24 passing through a slot 25 in the upper horizontal leg of the bracket and threaded into the bar 13.

Slidably mounted in a channel 26, formed in the under side of the bar 13, is block 27 to which is secured, by screw 27^a and suitable positioning pins, a plate 28 having oppositely inclined cam slots 29 which receive pins 30 projecting downwardly from the clamp arms 18. Thus sliding movement of the block 27 and plate 28 lengthwise of the bar 13 will cause the clamp-jaws 19 to be opened or closed, as is well understood. On the upper face of the bar 13 there is slidably mounted a retainer plate 31 which is connected with the slide-block 27 by screws 32 and 33 passing through a slot 34 in the bar 13. The slide-block 27 and plates 28 and 31 are normally urged forwardly, thereby tending to close the clamp-jaws 19, by a coil spring 35 connected at its opposite ends to the screws 24 and 32. A stop-shoulder 36 (Fig. 3) formed on a plate 37, adjustably secured on the upper face of the clamp-supporting bar 13, by screw 38, is adapted to engage the forward edge of the plate 31 thereby to limit the forward movement thereof and consequently the inward movement of the clamp-jaws. The stop-shoulder 36 is usually so adjusted that the clamp-jaws will normally move toward each other to positions in which they afford between them a space only slightly less than the width of the article to be clamped by the jaws. This obviates the necessity of completely opening the jaws each time an article is to be inserted. A hand-lever 39 projecting from one side of the plate 31 serves as means for man-

ually opening the clamp-jaws in opposition to the spring 35.

At the completion of a sewing cycle the work-clamp is lifted, about its fulcrum 15 to release the work-piece held on the work-supporting feed-plate 10 to permit the article to be removed from the clamp. Lifting of the work-clamp is effected, as is common in this type of machine, by manually lifting a spring-depressed bar 40 slidably mounted in the bracket-arm head 4. At its lower end the bar 40 carries an arm 41 which underlies the upper leg 42 of a U-shaped bracket 43 secured upon the bar 13 by screws 44. Thus lifting of the bar 40 lifts the forward end of the work-clamp. Upward movement of the work-clamp may be utilized to effect automatic separation of the clamp-jaws 19. This is effected by means of a bell-crank lever 45 fulcrumed on a screw 46 carried by a bracket 47 secured upon the upper face of the bar 13. The lower arm 45^a of the lever 45 abuts against one end of a plate 48, adjustably secured upon the plate 31 by screw 49, while the upper arm thereof underlies and is adapted to engage an abutment block 50 adjustably secured upon a bracket 51 carried by a fixed stud 52 secured in the lower end of the bracket-arm head 4. Upward movement of the work-clamp causes the arm 45^b of the lever 45 to engage the block 50 whereupon the lever is rotated counterclockwise, as viewed in Fig. 1, thereby shifting the slide-block 27 and slotted plate 28 rearwardly thus causing the clamp-arms 18 to be moved outwardly in opposition to the spring 35.

During the stitching cycle the entire work-holder is moved lengthwise of the work-supporting arm and the forward end thereof is moved crosswise of the arm and relative to the stitch-forming mechanism. This is effected, as is common in this type of sewing machine from suitably shaped cam grooves (one of which is shown) formed in the opposite faces of a rotary cam wheel 53, through the medium of mechanism designated generally as x. Inasmuch as this specific clamp-actuating mechanism forms no part of the present invention detailed illustration and description thereof is deemed unnecessary. Suffice it to say that the mechanism shifts the work-holder and the material and article carried thereby relative to the stitching mechanism to cause the formation of a series of article-attaching stitches as shown in Fig. 9.

As hereinbefore stated, this invention relates primarily to the means for supporting the fabric material m and the parachute releasing cone C to be attached thereto. The feed-plate 10, on which the material m is placed, is formed with a central opening 54 of irregular shape affording inwardly projecting work-supporting fingers 55, which underlie the flange y of the cone C, and notches 56, located outside the periphery of the flange y, through which the needle passes in making certain ones of the article-attaching stitches. The feed-plate 10 is also formed in its upper face with surface cavities 10^a, 10^b and 10^c into the first two of which the material m is adapted to be depressed by the clamp-arms 18 and jaws 19 while a presser-foot 20^a, forming a part of the article-holding jaw 20, depresses the material m into the surface cavity 10^c.

The flange y of each cone C is formed with a plurality of stitch-receiving holes a, b, c, d, e, f, g and h and two semi-circular notches i which are entered by a portion of the jaws 19 to locate

the cone relative to the stitch-forming mechanism.

Each article-holding jaw 19 is pivotally connected to the free end of one of the clamp-arms 18 by a screw 57 and is held in adjusted position thereon by means of a clamp-screw 58 passing through a clearance aperture 59 and threaded into the end of the clamp-arm. Also, each jaw 19 has formed therein a cone-flange receiving kerf 60, which, for easy insertion of the cone-flange therein, is slightly greater in width than the thickness of the flange. The third jaw 20 also has a similar kerf 60^a therein to receive the flange of the cone at approximately 90 degrees from the jaws 19. Each jaw 19 also carries a stud 61 which intersects the kerf 60 and presents therein a semi-circular portion adapted to fit within one of the cone-locating notches *i*, thereby interlocking the jaw with the periphery of the flange *y* of the cone C.

As hereinbefore stated considerable difficulty has been experienced in quantity production of work-holders for articles of this nature due to the fact that any slight variation of the parts or in their assembly may cause the cone to be slightly rotated about its axis from the intended position thereby throwing the stitch-receiving holes in the flange out of line with the needle. This difficulty has been overcome by the angular adjustment of the jaws 19 about the screw 57. Adjustment of one jaw in one direction and the other jaw in the opposite direction, relative to the cone, will cause the cone to be rotated clockwise while opposite adjustment of the jaws will effect counterclockwise rotation of the cone. In some instances it may be necessary to adjust only one jaw thereby causing the cone to be turned bodily about the opposite studs 60. It will be understood that ordinarily these adjustments of the jaws will be required only once for each machine, that is after the machine and the clamp have been completely assembled. After the clamp-jaws have once been adjusted to cause the needle to properly enter the stitch-receiving holes in the flange of the cone C the jaws are clamped in that position and no further adjustment is required provided all the cones and the location of the stitch-receiving holes and locating notches *i* therein are identical.

Operation of a sewing machine fitted with this improved clamp is as follows:

The operator, by manipulation of a suitable lever, not shown, raises the spring-depressed bar 40 and thereby lifts the clamp from the work-supporting feed-plate 10. Next she places the fabric *m* on the feed-plate and inserts the flange of a cone C into the kerfs 60 in the jaws 19 and kerf 60^a in the combined jaw and presser-foot 20 with the studs 61 entering the cone-positioning notches *i*. Should any angular adjustment of the cone be required to cause the needle properly to enter the holes in the flange of the cone this is then done by oppositely adjusting the clamp jaws 19 as hereinbefore described. The operator then releases the clamp-lifting lever thereby permitting the clamp to descend under spring pressure. The jaws 19 and 20 descend into the surface cavities 10^a, 10^b and 10^c to a position below the upper surface of the feed-plate 10 while the material overlying the fingers 55 limits the downward movement of the cone. This permits the clamp jaws to have a further downward movement after the cone has been brought to rest thereby causing the upper walls of the kerfs to be brought forcibly into contact

with the upper face of the flange of the cone thereby securely to clamp the flange upon the fabric and rigidly support it and prevent it from rocking during the sewing operation.

5 Next the operator trips the sewing machine into operation whereupon the needle first descends through the stitch-receiving hole *a* in the flange of the cone (see Figs. 8 and 9 and the needle-thread loop will be taken by the loop-taker in the usual manner. As the needle rises, the work-holder and the body material and cone carried thereby are shifted so that in its next descent the needle steps over the edge of the flange and penetrates the body material at *a'*. 10 In its third descent the needle again passes through the hole *a* thus having placed two stitches over the flange of the cone between *a* and *a'*. In its fourth descent (the material and cone having been further shifted) the needle passes through the hole *b* in the flange of the cone. This cycle is repeated through the holes *c*, *d*, *e*, *f*, *g*, and *h* and over the edge of the flange until the machine has sewed completely around the cone and the needle has again descended through the initial hole *a*. 15 Then the needle makes one complete traverse about the cone sewing through the holes without stepping over the edge of the flange. This again brings the needle into the hole *a*. After that the needle descends three times in succession through the fabric at *a'* thereby producing tying stitches as is well understood, thus completing a 36-stitch sewing cycle after which the machine is stopped 20 automatically.

35 Having thus set forth the nature of the invention, what I claim herein is:

1. A work-holder for an article-attaching machine having stitch-forming mechanism, comprising a work-supporting plate; a plurality of 40 article-holding jaws pivotally supported above said plate to hold an article to be attached to a work-piece held on the plate, one of said jaws having a portion adapted to effect an interlocking engagement with the periphery of the article 45 therein; and means for angularly adjusting said one of said jaws about its pivot to effect angular adjustment of the article held therein relative to the stitch-forming mechanism.

2. A work-holder for an article-attaching machine comprising a work-supporting plate; a pair of pivoted work-clamping arms located above said plate for holding a work-piece thereon; a pair of article-holding jaws pivotally mounted on said work-clamping arm and having portions adapted to interlock with apertures in the opposite edges of substantially circular articles; and means for angularly adjusting said jaws on said arms in opposite directions to effect rotary adjustment of said article about its axis.

3. A work-holder for an article attaching machine comprising a work-supporting plate; a plurality of spring-depressed work-clamping members adapted to clamp a workpiece on said plate; an article-stopping and holding jaw provided by one of said work-clamping members and adapted to engage the marginal portion of a substantially circular article and depress it into contact with said work-piece; a pair of article-holding jaws each pivotally mounted on one of said work-clamping members and engaging opposite marginal portions of the article at approximately 90 degrees about the periphery thereof from the first named jaw, each of said pair of article-holding jaws having a portion

adapted to effect an interlocking engagement with the periphery of the article therein; and means to effect angular adjustment of each of said pair of jaws about its pivot to effect, through said interlocking engagement, rotary adjustment of said article about its axis.

4. A work-holder for an article-attaching machine as set forth in claim 3, in which each article-holding jaw is formed with a horizontally disposed kerf adapted to receive a portion of the article to be attached and in which each of said pair of article-holding jaws is provided with a portion which projects into the kerf therein and is designed to fit within a notch formed in the periphery of the article to prevent rotation of the article relative to the jaws.

5. A work-holder for an article-attaching machine as set forth in claim 3, in which each article-holding jaw is formed with a horizontally disposed kerf adapted to receive a flange on the article to be attached, and in which each of said pair of article-holding jaws has an article locating and holding stud intersecting said kerf

and designed to fit within a notch formed in the periphery of the flange of the article to prevent relative rotation between the article and the jaws and to effect rotation of the article about its axis when said pair of jaws are angularly adjusted in opposite directions.

6. A work-holder for an article-attaching machine comprising a fabric-supporting plate having a central aperture, a plurality of work-supporting fingers projecting into said aperture and a plurality of surface cavities on the upper face of the plate; a plurality of spring-depressed work-clamping members for depressing portions of a work-piece into said cavities with other portions thereof supported on said fingers; article-holding jaws carried by said work-clamping members for holding a substantially circular article on said work-piece above said fingers; and means for angularly and oppositely adjusting two of said article-holding jaws to effect rotary adjustment of said article about its axis.

HERMANN GUNTHER.
